(57) **CLAIM**

The ornamental design for a filtering facepiece respirator, as shown and described.

DESCRIPTION

FIG. 1 is a front perspective view of a first embodiment of the filtering facepiece respirator showing the present design in a configuration of use;

FIG. 2 is a front view of the filtering facepiece respirator shown in FIG. 1;

FIG. 3 is a rear view of the filtering facepiece respirator shown in FIG. 1;

FIG. 4 is a left view of the filtering facepiece respirator shown in FIG. 1;

FIG. 5 is a right view of the filtering facepiece respirator shown in FIG. 1;

FIG. 6 is a top view of the filtering facepiece respirator shown in FIG. 1;

FIG. 7 is a bottom view of the filtering facepiece respirator shown in FIG. 1;

FIG. 8 is an environmental view of the filtering facepiece respirator shown in FIG. 1;

FIG. 9 is a front view of the filtering facepiece respirator shown in FIG. 1 in a folded configuration;

FIG. 10 is a rear view of the filtering facepiece respirator shown in FIG. 1 in a folded configuration;

FIG. 11 is a front perspective view of a second embodiment of the filtering facepiece respirator shown a configuration of use;

FIG. 12 is a front view of the filtering facepiece respirator shown in FIG. 11;

FIG. 13 is a rear view of the filtering facepiece respirator shown in FIG. 11;

FIG. 14 is a left view of the filtering facepiece respirator shown in FIG. 11;

FIG. 15 is a right view of the filtering facepiece respirator shown in FIG. 11;

FIG. 16 is a top view of the filtering facepiece respirator shown in FIG. 11;

FIG. 17 is a bottom view of the filtering facepiece respirator shown in FIG. 11;

FIG. 18 is an environmental view of the filtering facepiece respirator shown in FIG. 11;

(Continued)

FIG. 19 is a front view of a second embodiment of the filtering facepiece respirator of FIG. 11 shown in a folded configuration; and,

FIG. 20 is a rear view of the filtering facepiece respirator of FIG. 11 shown in a folded configuration.

The broken lines in the figures depict portions of the filtering facepiece respirator that form no part of the claimed design. The broken lines illustrating a head in FIG. 8 and FIG. 18 represent environment which forms no part of the claimed design.
